To all whom it may concern:

A represents a clock-case, having molded base B and arched top C. To the ends of the molding of the arched top are attached the large ends of the conical tips D D', which may be plain or carved in any desired shape. To the base B are attached the conical tips D'' D''', which are similar to the tips D D', but preferably a little longer, the plain surface E being left between the tips.

What I claim as my invention is—
